UNITED STATES PATENT OFFICE.

EDWARD A. THIEM, OF ST. PAUL, MINNESOTA.

TOE-CLIP FOR BICYCLES.

SPECIFICATION forming part of Letters Patent No. 574,286, dated December 29, 1896.

Application filed March 5, 1895. Serial No. 540,629. (No model.)

To all whom it may concern:

Be it known that I, EDWARD A. THIEM, a citizen of the United States, residing at St. Paul, in the county of Ramsey and State of Minnesota, have made certain new and useful 5 Improvements in Toe-Clips for Bicycles, of which the following is a specification.

My invention relates to improvements in bicycle toe-clips, its object being to provide 10 a clip which will embrace the foot so as to hold it to the pedal, and which will also furnish a continuous support over the foot, so as to withstand the strain of a sudden stop or the hard pull in coming up steep grades where 15 it is desired to pull up on the pedals.

To this end my clip is made up of a toe-receiving bend and a foot-embracing loop, said loop and bend being intertwined or interlocked upon the top of the foot, and the foot- 20 embracing loop being preferably formed with reverse rearwardly-extending bends adapted to furnish a support for the instep. The ends of the foot-loop are preferably slidably interlocked beneath the foot, so as to be secured 25 in adjusted positions to the pedal. The end of the toe-holding bend also passes underneath the foot and is adjustably connected to the interlocked ends of the foot-embracing loop. I am thus able to adjust both the 30 width and height of the clip so as to fit it to any size or shape of shoe. With the clip adjusted to fit the shoe of the rider a firm continuous support is furnished entirely around the foot, there being no parts which can be 35 separated by the strain of an upward pull. The rider can thus pull up on one pedal while pushing down upon the other, thereby greatly increasing the driving power.

My invention further consists in the construction hereinafter more particularly described and claimed.

In the accompanying drawings, forming part of this specification, Figure 1 is a perspective view of one of the ordinary pedals 45 of a bicycle. Fig. 2 is a similar view of my improved toe-clip. Fig. 3 is a view of a portion of the clip, illustrating a modification in the manner of connecting the foot-embracing loop and toe-holding bend; and Figs. 4 and 50 5 are details of the lower portion of a modified form of clip in which the same is attached

to the pedal without means for lateral adjustment of the foot-embracing loop.

In the drawings, A represents the ordinary bicycle-pedal, to the side bar 2 of which is 55 adapted to be secured my improved toe-clip B. This clip is made up of the foot-embracing loop 3 and the toe-holding bend 4, preferably formed of a single piece of wire inter-twisted or interlocked together at 5 for the 60 purpose more fully hereinafter described. The foot-embracing loop is formed upon each side of its connection with the toe-holding bend 4, with rearwardly-projecting bends 6. These bends bear upon the instep of the foot 65 and furnish a better lifting-support.

The ends of the wire constituting the foot-embracing loop are each formed with an eye 7, encircling the opposite member, thus permitting the loop to be adjusted to fit different- 70 sized shoes. The bend 4 extends around the toe and underneath the foot, its end 8 being downturned adjacent the interlocking ends of the foot-loop.

For securing the clip to the pedal I provide 75 the clamp-plate 9, which is fitted over the interlocked ends of the foot-embracing loop and is provided with an opening 10, through which the securing-bolt 11 is passed, the bolt projecting through the opening 12 in the side of 80 the pedal and being secured by a nut 13.

The end 9 of the bend 4 may be raised or lowered to vary the height of the clip and the sides of the foot-embracing loop separated or closed to vary its width, the parts being held 85 in such adjusted positions by means of the connection with the pedal.

Fig. 3 illustrates a modified form of connection between the toe-holding bend and foot-embracing loops. In this form the parts are 90 secured together by means of a sheet-metal clamp or sleeve 15, instead of being inter-twisted, as shown in Fig. 2.

Figs. 4 and 5 illustrate my toe-clip with the ends of the foot-embracing loop formed with 95 eyes 14 to receive the securing-bolt, instead of being adjustably connected, as shown in Fig. 2. Otherwise the construction of the clip is the same as my preferred construction.

In both forms of my clip I firmly intertwist 100 or interlock the foot-embracing loop and toe-receiving bend, thus securing a continuous

stirrup-like support around the foot for the purposes above described, and which will not separate under the strain. This is the important feature of my invention. In those 5 clips which have guards the side guards either do not extend up over the foot or else they are not connected at the top, and thus become separated by the hard lifting strain.

Having thus described my invention, what

10 I claim as new is—

1. A toe-clip for bicycles formed of a single piece of wire comprising a foot-holding section and a toe-embracing section with the ends of the wire underlapping beneath the ball of the 15 foot and having eyes upon the ends embracing the adjacent underlapping sections, and means for coupling said clip to a pedal to permit the lateral adjustment of the adjacent underlapping sections, to vary the width of 20 the clip, substantially as and for the purpose set forth.

2. As an improved article of manufacture, a toe-clip of the class described, comprising a foot-embracing loop secured to the pedal in 25 substantial alinement with the forward pedal-plate, and a forwardly-projecting toe-receiving bend, whereby as the foot is in position upon the pedal, with the toe of the shoe projecting into the toe-loop, and the ball of the 30 foot standing between the front and rear of the pedal, the foot-embracing loop will bear upon the top of the foot in a vertical plane with the front pedal-plate, so as to furnish a support at that point in the upward pull of 35 the foot.

3. As an improved article of manufacture, a toe-clip of the class described, comprising a toe-holding bend and a foot-embracing loop connected thereto upon the top of the foot, 40 said foot-embracing loop having its ends adjustably connected underneath the foot to accommodate shoes of varying widths.

4. As an improved article of manufacture, a toe-clip of the class described, consisting of 45 a toe-receiving bend, adjustable side guards,

and means for securing the side guards at any desired width.

5. As an improved article of manufacture, a bicycle pedal-clip, comprising a toe-holding bend, a continuous foot-embracing loop connected thereto, and means for adjusting both the lateral and vertical dimensions of said clip, and securing the same in adjusted positions to the pedal. 50

6. As an improved article of manufacture, 55 a bicycle-pedal toe-clip, consisting of a foot-embracing loop, with the ends slidably connected underneath the foot, to permit of their relatively lateral adjustment, the toe-holding bend rigidly connected to the top of said foot- 60 loop, and engaging the interlocked ends of said first-named loop underneath the foot, and the clamp for securing the ends of said loop and bend in adjusted positions to the pedal.

7. As an improved article of manufacture, 65 a bicycle-pedal toe-clip, consisting of a single piece of wire forming the foot-embracing loop, and a toe-receiving bend rigidly connected thereto on the top of the foot, and with their 70 ends adjustably interlocked beneath the foot, and means for securing them in adjusted positions upon the pedal.

8. A toe-clip for bicycle-pedals, consisting of the toe-receiving bend, the adjustable side guards, and the bolt for securing the side 75 guards at any desired width and attaching the clip to the pedal.

9. The combination with the bicycle-pedal, of a toe-clip consisting of the U-shaped portion for the toe, the loop below, and the loops 80 above said portion, the side guards, and the clamping-bolt for securing the side guards at any desired width.

In testimony whereof I have hereunto set my hand in the presence of two subscribing 85 witnesses.

EDWARD A. THIEM.
